UNITED STATES PATENT OFFICE.

ERNST WESSER, OF LEIPZIG, GERMANY.

CYLINDER PRINTING-MACHINE.

SPECIFICATION forming part of Letters Patent No. 773,444, dated October 25, 1904.

Application filed June 5, 1903. Serial No. 160,244. (No model.)

To all whom it may concern:

Be it known that I, ERNST WESSER, a subject of the German Emperor, residing at 21 Plagwitzerstrasse III, Leipzig, Germany, have 5 invented certain new and useful Improvements in Cylinder Printing-Machines; and I do hereby declare the following to be a full, clear, and exact description of the invention, such as will enable others skilled in the art to which it applies to make and use the same.

This invention relates to a cylinder printing-machine for printing breadths of wall-paper and the like by means of which parts of patterns in the form of strips of varied 15 color, as well as the parts in monotone serving to connect them, can be printed under a single continuous working operation.

In the accompanying drawings the device is shown as applied to a wall-paper-printing machine.

Figure 1 is a longitudinal section through the color-boxes with the color-feeding cylinder mounted therein and divided into a number of parts. Fig. 2 is a diagram illustrating 25 the laying on of the color; Fig. 3, a plan of the color-feeding cylinder with color-boxes; Fig. 4, a plan of the whole printing device. Fig. 5 represents a pattern in five colors with corresponding color-feeding cylinders.

30 In the form illustrated in Figs. 1 to 5 it is assumed that a pattern in five colors is to be printed, for which purpose a color-feeding cylinder in four parts or lengths and an undivided color-feeding cylinder are employed.

35 Correspondingly to the division of the color-feeding cylinder *a* (see Figs. 1, 3, and 4) the color-boxes *b* are also divided into four parts, so that each part can be interchanged independently of the others. The different colors in the boxes *b* are conveyed to the color-band *d* in the usual way by means of the cylinders *a* (see Figs. 2 and 4) and appear, as shown in Fig. 4, in four separate strips on the color-bands, by which the suitable parts of 40 the pattern-cylinder *g* are colored, so that the cylinder *g* prints simultaneously in four colors.

In order that the pattern may be of a more homogeneous character, the leaves, branches, and the like are printed with a cylinder *g'*, 50 which occupies the whole breadth of the paper, the color-band *d'* of which is furnished with a color in the ordinary way by an undivided

color-feeding cylinder *a'*, which of course rotates in an undivided color-box *b'*.

In order that any color dropping off the 55 color-bands *d* may not reach any adjoining color-box, but always be conveyed again to the proper color-box, a bar *h*, with curved depending strips *h'*, is arranged to bear lightly against the color-band *d*, being placed above 60 the divided applying-cylinder *a*, with the strips between each two parts of the cylinder

What I claim, and desire to secure by Letters Patent, is—

1. In a cylinder printing-machine of the 65 character described, the combination with a divided color-box, of a divided color-feeding cylinder, the sections of which are rotatably mounted in the sections of the divided color-box, a color-band arranged to receive the colors from the sections of the color-feeding cylinder, a pattern-cylinder arranged to receive the colors from the color-band, and a bar arranged above the color-feeding cylinder transversely of and bearing against the color-band 70 75 and having depending strips arranged to direct any colors dropping from the color-band back into the respective sections of the color-box.

2. In a cylinder printing-machine of the 80 character described, the combination with a divided color-box, of a divided color-feeding cylinder, the sections of which are rotatably mounted in the sections of the divided color-box, a color-band arranged to receive the colors from the sections of the color-feeding cylinder, a pattern-cylinder arranged to receive the colors from the color-band, a bar arranged above the color-feeding cylinder transversely of and bearing against the color-band and having 85 90 depending strips arranged to direct any colors dropping from the color-band back into the respective sections of the color-box, an undivided color-box, an undivided color-feeding cylinder rotatably mounted therein, a color-band arranged to receive the color from said band, and a printing-cylinder *g'* arranged to receive the color from the last-named band. 95

In testimony whereof I have affixed my signature in presence of two witnesses.

ERNST WESSER.

Witnesses:

HEIN. SACHS,
RUDOLPH FRICKE.
